UNITED STATES PATENT OFFICE.

JOHN CUTHBERT, OF CHICAGO, ILLINOIS, ASSIGNOR TO JOHN CUTHBERT COMPANY, OF CHICAGO, ILLINOIS, A CORPORATION.

CABINET STRUCTURE FOR PANEL-BOARDS.

1,360,374.

Specification of Letters Patent. Patented Nov. 30, 1920.

Application filed November 5, 1915, Serial No. 59,731. Renewed May 3, 1920. Serial No. 378,653.

To all whom it may concern:

Be it known that I, JOHN CUTHBERT, a citizen of the United States, residing at Chicago, in the county of Cook and State of Illinois, have invented certain new and useful Improvements in Cabinet Structures for Panel-Boards, of which the following is a specification.

My invention relates to improvements in cabinet structures for electrical panel boards, and more particularly to a construction embodying a flush type cabinet with detachable cover plate.

One of the objects of my invention is to provide a cabinet for electrical panel boards in which the cover plate with its door may be readily removed from or attached to the box body by means accessible only from the interior of the cabinet.

Another object is the provision of a cabinet having a removable cover plate carrying a rearwardly extending wall section which with the panel board divides the space within the cabinet into two compartments, the outer of which is open to inspection on the opening of the door in the cover plate, and the inner of which is opened only on the removal of the entire plate.

Another object of my invention is the provision of such a structure in which the walls of the outwardly opening compartment are adapted for the reception of markers indicating the adjacent circuit connections.

Another object of my invention is the provision of a structurally rigid, strong, substantial cabinet so arranged that the wiring of the panel board may be accomplished in a most economical and efficient manner.

Other and further objects will become apparent to those skilled in the art from a consideration of the following description and drawing, wherein:

Figure 1 is a front elevation of my improved cabinet with parts broken away.

Fig. 2 is a horizontal sectional view on the line 2—2 of Fig. 1.

Fig. 3 is a vertical sectional view on the line 3—3 of Fig. 4, and;

Fig. 4 is a vertical sectional view on the line 4—4 of Fig. 3.

Referring to the drawings illustrating a

preferred embodiment of my invention, shown for the purpose of clear disclosure, it will be noted that the cabinet comprises in general two sections, one a box shaped receptacle within which is mounted the panel board and into which lead the conduits for the wiring, and the other comprising a face section or cover plate for the box having in its central portion a hinged door. Inside the edges of the aperture covered by the door I have provided inwardly extending walls or flanges which contact with the periphery of the panel board forming an outwardly opening box within which the face of the panel board alone is exposed.

Referring to the drawings in detail, the numeral 10 indicates in general a rectangular box having a back wall 11, vertical side walls 12—12 and top and bottom walls 13—13. The box is open at its face and has short inturned lips or flanges 14—14 for a purpose to be described.

Within the box is mounted a panel board of any desired type, the one illustrated at 15 carrying fuse plugs, connection being made with the back wall 11 in any suitable manner as indicated in dotted lines in Fig. 2. The walls of the box 10 are provided with "knock-outs" 16 through which the conduits for the wiring system may be led.

Overlying the front or face of the box 10 is a detachable cover plate indicated in general by the numeral 17. In the specific embodiment illustrated this cover plate comprises a rectangular flat plate 18 extending somewhat beyond the walls of the box 10 and having an opening 19 formed in its center portion to receive the flush door 20. I have illustrated the door 20 as being connected with the plate 18 by means of an improved concealed hinge 21 which is fully illustrated and described in my copending application for improvements in "concealed hinges" filed by me October 12th, 1915 and serially numbered 55403.

Extending inwardly from the cover plate 18 at the marginal edges of the opening 19 and secured to said plate is a rectangular structure comprising four walls 22 joined at their corners and adapted to make contact with the side surfaces of the panel board 15. These walls, together with the panel board

15, which serves as a back for the walls, divide the space within the box 10 into two compartments, the one indicated by the numeral 23 having the panel board as its base, 5 the walls 22—22 as its sides and the door 20 as its front, opening to the exterior of the box and exposing to view only the face portion of the panel board. The second compartment 24 surrounds the compartment 10 and is made sufficiently large to receive and contain the wires connected to the panel board. The part 22', of the wall 22, is practically parallel with the door 20 and extends inwardly of the door opening 15 in the cover plate so that when the door is closed it rests against the flat part 22'—Fig. 2. This part 22', therefore, provides a stop or rabbet for the door, preventing it from swinging farther inwardly and bridging 20 the adjacent edges of the door and the cover plate.

The cover plate 18 is detachably connected to the front edge of the box 10 by means of sliding fingers or prongs 25 secured to the rear face of the cover plate 18 by means of screws or rivets 26 projecting through slots 27. This connection permits an endwise movement of the fingers 25 into or out of engagement with the flanges 14. 30 The inner ends of the fingers 25 extend through openings in the walls 22 and are bent downwardly as at 28 to lie out of the way and parallel with the walls and permit ready operation thereof. Humps 25' are 35 formed on the fingers to engage an edge of the slots through which they pass and thus lock the fingers in either extreme position. Near where the downturned parts 28, of the fingers 25, pass into the center compartment 40 23, the fingers are sprung inwardly and encounter the edge of the wall 22 at the openings. To move the locking fingers laterally to engage or disengage the flange 14, of the box, it is necessary to press on the ends 28 45 until the humps 25' will pass through the openings. The humps will prevent the fingers from being returned until they are again depressed.

A series of tongues 29 are struck up from 50 the walls 22 and provide pockets for holding marker tabs 30 to indicate the circuits to which the adjacent apparatus is connected.

It is obvious from the above description 55 that in setting up the cabinet the box body 10 is first set in the wall and the wiring connections readily made with the panel board, the operator having the entire open space within the box in which to work. Obviously the wires may be extended from one 60 side of the box to connect with the panel board at the opposite side or in fact any cross connections may be made that ordinarily would not be permitted in a box of 65 usual type. After the wiring has all been

placed, the cover plate 18 is then placed against the edges of the box 10 flush with the wall and the fingers 25 driven home by a hammer blow on the inturned ends 28. The cover plate is thus securely locked in place and all of the wiring is concealed within the compartment 24, the compartment 23 being the only part exposed to view. For inspection of the wiring the inturned ends 28 are readily pulled inwardly by 75 means of a screw driver or other tool, after which the cover plate 18 may be removed from the box exposing the wiring to view.

Whereas I have illustrated and described a single embodiment of my invention, it is 80 obvious that various changes might be made in the same without departing from the spirit and scope of the appended claims.

Having described my invention, what I claim is:

1. A cabinet for a panel board comprising an open faced box adapted to receive a panel board; a detachable cover plate adapted to overlie the opening in the box, said cover plate having a door receiving opening, and wall sections secured to and carried by the cover plate removable therewith and extending inwardly and rearwardly into substantial contact with the periphery of the panel board, dividing the space within the box into two compartments and inseparable means to bridge the joint between the margin edge of the door and said door opening.

2. A cabinet for a panel board comprising a box member adapted to receive a panel board; a cover plate therefor having a door opening; a door hinged flush with said cover plate in said opening; rearwardly directed walls secured to and removable 105 with said plate extending inwardly of the door margin to provide a rabbet and extending rearwardly to divide the box into two compartments and to closely surround and partly overlap the panel board.

3. A cabinet for a panel board comprising a box member adapted to receive a panel board and having its walls inturned to provide flanges; a cover plate therefor having a door opening; a door hinged to the plate 115 to cover the opening; walls extending rearwardly from the cover plate to divide the box into a central compartment and a surrounding compartment and laterally movable bolt fingers extending from the central 120 compartment through the surrounding compartment engaging said flanges to hold the cover plate in place on the box member.

4. In combination with an open face box adapted to receive a panel board, a detachable one piece cover plate adapted to overlie the opening in the box, said cover plate having a door-receiving opening; wall sections carried by and removable with the cover-plate extending rearwardly toward 125 130

and terminating near the bottom of the box, substantially dividing the box into two compartments, the central compartment to contain the panel board; a door carried by the cover-plate to close the opening therein and means to secure the cover plate to the box.

5 In testimony whereof I hereunto set my

hand in the presence of two subscribing witnesses.

JOHN CUTHBERT.
